COUCH

Joseph W. Bowersox, Glen Ellyn, Ill., assignor to
Superior Felt & Bedding Co., Chicago, Ill., a
corporation of Delaware

Application March 9, 1936, Serial No. 67,888

3 Claims. (Cl. 5—44)

The present invention relates to improvements in couches, and has particular reference to a new and improved couch having a plurality of relatively adjustable units arranged for assembly 5 to constitute a davenport or sofa, and for separation to provide twin beds.

One of the objects of the invention is to provide a new and improved couch of the foregoing character in which the two units when assembled 10 constitute the seat and back rest of a davenport or the like.

Other objects and advantages reside in the provision of various novel features of construction, such as means for guiding the horizontally 15 movable unit, means for positioning and supporting the swinging unit selectively in an upright position or a horizontal position, means for interlocking the horizontal unit and the couch frame against independent lifting, and 20 means on the horizontal unit for concealing the separable character of the units.

A general object is to provide a twin studio couch which is simple and inexpensive in construction, easy and convenient to operate, and 25 attractive in appearance.

Further objects and advantages will become apparent as the description proceeds.

In the accompanying drawings, Figure 1 is a perspective view of a studio couch embodying the 30 features of my invention.

Fig. 2 is a transverse vertical sectional view on an enlarged scale of the couch shown in Fig. 1.

Fig. 3 is an end elevational view of the couch illustrating the horizontal unit in withdrawn 35 position.

Fig. 4 is an end elevational view similar to Fig. 3, but with the swinging unit in horizontal position.

Fig. 5 is a fragmentary front elevational view 40 taken along line 5—5 of Fig. 3.

Fig. 6 is a fragmentary detailed sectional view taken along line 6—6 of Fig. 3.

Fig. 7 is a plan view, partially in section, of the construction shown in Fig. 3.

Fig. 8 is a fragmentary detailed sectional view 45 taken substantially along line 8—8 of Fig. 2.

Referring more particularly to the drawings, the couch, constituting the exemplary embodiment of the invention, is of the "studio" or "sofa bed" type, comprising twin upholstered spring 50 beds units 1 and 2 which are adapted to be assembled, as illustrated in Figs. 1 and 2, so as to afford seating facilities, or to be separated, as shown in Fig. 4, so as to provide extra sleeping accommodations. When the units 1 and 2 are

assembled, the couch assumes the form and normal appearance of a davenport or sofa, the unit 1 constituting the seat and the unit 2 serving as an upright back. Associated with the units 1 and 2 is a hidden stationary base frame 3 adapted to be supported directly on the floor. The seat unit 1 normally overlies and encloses the frame 3, but may be slidably withdrawn to uncover the latter. The back unit 2 is operatively connected to the frame 3, and adapted to be supported thereby either in a vertical position, or in a horizontal position at substantially the same level as the unit 1 when the latter is removed from the frame. In tilting or swinging the unit 2 into horizontal position over the frame 3, the 15 rear of the unit becomes the top.

In its preferred form, the frame 3 is made of metal, and comprises two horizontal cross bars 4 and 5 at the ends resting directly on the floor. The front ends of the bars 4 and 5 are bent upwardly and rigidly connected by a horizontal, longitudinal elevated front bar 6. Two vertical straps or legs 7 and 8 are secured respectively to the rear end portions of the bars 4 and 5, and are connected by a horizontal longitudinal elevated rear bar 9. Connecting the very ends of the bars 6 and 9 are two elevated horizontal cross rails 10 and 11 which serve as guides for the sliding unit 1 and also as the support for the unit 2. Preferably, the members 4 to 10 are in 30 the form of angle irons securely bolted or riveted together. As to the guiding function of the rails 10 and 11, it will be seen upon reference to Fig. 8 that these rails are positioned partially within recesses formed in the rear legs of the 35 unit 1 and overlie the brackets which carry casters 22 as well as the bottom walls of the leg recesses. Thus upward movement of the unit 1 is prevented as it is slid in and out. This guiding action which prevents upward movement of 40 the unit 1 during its withdrawal and retraction prevents a vertical strain being placed on the lost motion linkage which connects the unit 1 with the frame 3.

Rigidly secured to the rear end portions of 45 the bars 4 and 5, and projecting laterally therefrom beneath and outwardly beyond the rails 10 and 11 are two short flat bars or strips 12 and 13 which constitute lugs resting directly on the floor, and the upper surfaces of which are curved 50 or rounded transversely for a purpose herein-after described.

The seat unit 1 has a hollow base frame 14 adapted to slide over and receive the couch frame 3. A suitable upholstered spring cushion 15 is 55

built on and fully overlies the top of the frame 14. A depending apron 16 of a suitable material, such as wood, is secured to, and skirts, the front and ends of the frame 14. The apron 16 extends almost to the floor, and obviously fully conceals the frame 14, and also the couch frame 3 when the unit 1 is in retracted position. Ornamental depending projections 17, simulating legs, are provided at the front and rear corners of the 5 apron 16. The cushion 15 and the apron 16 may be covered with the same kind of upholstering material with a decorative bead 18 at the seam. It will be evident that the unit 1 as 10 constructed appears in every respect as the seat 15 of an ordinary davenport or sofa without end arms, and that the structural features permitting adjustment of the unit for use as a day bed or studio couch are concealed from casual observation, thereby enhancing the appearance and 20 character of the couch while retaining its full utility for the purpose intended.

The unit frame 14 has rigid depending front and rear legs 19 and 20 which are enclosed by the apron 16, and which have casters 21 and 22 25 at their lower ends to support the unit 1 directly on the floor. The front legs 19 are located inwardly from the ends of the frame 14 and in front of the elevated bar 6. The rear legs 20 are located at the very ends of the frame 14, 30 and are adapted to be guided by the rails 10 and 11 upon rearward movement of the unit 1 into position over the frame 3. The ends of the lugs 12 and 13 are disposed in the path of the casters 22. When the unit 1 is in fully retracted position, 35 as shown in Fig. 2, the casters 22 will engage the rear descending upper surfaces of the lugs 12 and 13 to prevent unwarranted movement in a forward direction.

Forward movement of the unit 1 is limited 40 by a releasable lost motion connection with the frame 3. This connection may be of any suitable character, and in the present instance is shown as comprising two long diagonal cross strips 23 and 24 (see Figs. 2 and 7) pivotally connected 45 at 25 midway of their ends. The forward end of the strip 23 is pivotally anchored to a bracket 26 fixed on the inside of the front portion of the apron 16, and the rear end has a pin 27 slidably engaging a longitudinal slot 28 in one end of 50 the bar 6 of the frame 3. The strip 24 at its rear end has a pin 29 removably and pivotally inserted in the other end of the bar 6, and at its front end has a pin 30 slidably engaging in a slot 31 formed in an elongated bracket 32 55 on the inside of the apron 16.

It will be evident that the strips 23 and 24 will permit movement of the unit 1 entirely off the frame 3, and will determine the outermost position as illustrated in Figs. 3 and 4. This position is such that the back unit 2, when swung into the horizontal, will be located immediately alongside the unit 1, so that the two units may be used separately or as a double bed. The strips 23 and 24 also serve to guide the unit 1 in its 60 movement into retracted position or forward position. If it should be desired to move the units 1 and 2 apart, the pins 27 and 29 need merely be lifted from the bar 6, thereby effecting a complete separation of the unit 1 from the frame 3. 65 Secured to the inside of the front portion of the apron 16 immediately outside the legs 19 are two horizontal fingers 33 and 34 which project rearwardly closely over the bar 6 when the unit 1 is in retracted position. Two additional fingers 70 75 35 and 36 are secured to the inside of the apron

16 between the legs 19, and project rearwardly under the bar 6. By reason of the fingers 33 to 36, lifting either the unit 1 or the frame 3 at the front will result in the lifting of both.

The back unit 2 comprises a rectangular frame 37 having transverse end bars 38 and 39. With the unit 2 in vertical position, the frame 37 is covered at the front above the unit 1 by an upholstered spring sofa cushion 40, and over the entire rear by an upholstered spring bed cushion 41. The unit 2 is closed at the ends, and is recessed in its lower front portion, as indicated at 42, to receive and closely interfit with the rear portion of the unit 1 which projects partially beneath the cushion 40. 15

To provide means for supporting the unit 2 in either position of adjustment, the frame 37 is connected to the frame 3 at each end by two folding pivot links 43 and 44. Referring to Fig. 2, the link 43 is pivotally connected at its upper 20 end by means of a pin 45 to the middle portion of the cross member 39, and at its other end by means of a pin 46 to the rear end portion of the rail 11. Likewise, the link 44 is pivotally connected at opposite ends by means of pins 47 and 48 respectively to the lower end of the member 39 and an intermediate portion of the rail 11 forwardly of the pin 46. Projecting inwardly from the link 44 at a point adjacent the pin 48 and over the rail 11 into the path of the rail 43 is a 30 pin or projection 49.

The link construction at the other end of the couch, i. e., connecting the member 38 and the rail 10, is like that just described, and the corresponding parts thereof are identified by the 35 same reference characters. To obtain greater rigidity, the links 43 may be connected intermediate their ends by a bar 50 extending longitudinally of the couch and thus cooperating with this pair of links to form a swingable supporting 40 frame.

When the unit 2 is in upright position, as illustrated in Figs. 2 and 3, the rear ends of the links 44 will cross and rest against the top of the frame member 9. Most of the unit 2 in this position is 45 disposed rearwardly of the member 9, and hence the weight of the unit serves to hold the parts in position of adjustment. When the unit 1 is withdrawn from the frame 3, the upper portion of the unit 2 may be swung forwardly and downwardly 50 until the links 43 engage the pins 49, as illustrated in Fig. 4. In this position of adjustment, most of the unit 2 is disposed forwardly of the pins 49, and hence the weight of the unit serves to hold the parts in position of adjustment. 55

It will be evident that movement of the units into position to constitute a davenport or the like as illustrated in Figs. 1 and 2, or into horizontal position to constitute twin beds, as illustrated in Fig. 4, may be easily and quickly accomplished. 60 When the units are assembled, the construction in appearance is typically that of a davenport or sofa, and in no way simulates a form easily recognizable as a studio or sofa bed couch.

I claim as my invention:

1. A couch comprising, in combination, a frame having a longitudinal bar at the front, a horizontal bed unit having front and rear legs adapted for engagement with the floor and having a skirt extending substantially to the floor at 70 the ends and front to enclose said legs and to define an opening in the rear for reception of said frame, said unit being movable selectively into withdrawn position off of said frame or into retracted position over said frame, and a plurality of 75

of feet projecting from the ends of said frame into the path of the rear legs and adapted to coact therewith to hold said unit in retracted position.

5 2. In a couch comprising a base frame and a horizontal bed unit having an opening in the rear thereof for reception of said frame and legs adapted for slidable engagement with the floor to permit movement of the unit selectively 10 into withdrawn position off of said frame or into retracted position over the frame, the combination of feet projecting from said frame along the floor surface in the paths of said bed-unit legs and adapted to coact therewith to hold said unit 15 in retracted position.

10 3. A couch comprising, in combination, a frame having cross rails at the ends and a longitudinal bar at the front, a horizontal bed unit having front and rear legs adapted for engagement with

the floor and having a skirt extending substantially to the floor at the ends and front to enclose said legs and to define an opening in the rear for the reception of said frame, said unit being movable selectively into withdrawn position off of 5 said frame or into retracted position over said frame, means including said rails positioned to coact with the rear legs for guiding said unit in its withdrawal and retraction movement to limit vertical movement of said unit, and a plurality 10 of sets of fingers mounted on the front section of said skirt and adapted to project rearwardly therefrom into position respectively above and below said bar when said unit is in retracted position, whereby to assure that lifting movement 15 imparted to the bed unit will be transmitted to the frame and vice versa.

JOSEPH W. BOWERSOX.
